GB 2598489 A * 3/2022 ..... E03C 1/021

Primary Examiner — Richard E Chilcot

(57) **CLAIM**

The ornamental design for a tap, as shown and described.

DESCRIPTION

1. Tap

2. Tap

Figure 2.1 is a perspective view showing the top, and left side of the tap of the present invention;

Figure 2.2 is a perspective view showing the top and right side thereof;

Figure 2.3 is an elevation view of the left side thereof;

Figure 2.4 is an elevation view of the right side thereof;

Figure 2.5 is an elevation view of the front thereof;

Figure 2.6 is an elevation view of the back thereof;

Figure 2.7 is a plan view of the top thereof; and

Figure 2.8 is a plan view of the bottom thereof.
